UNITED STATES PATENT OFFICE

115,646

DESIGN FOR A LUBRICANT DISPENSING APPARATUS

Arthur Fuller Dean, Winnetka, Ill., assignor to Stewart-Warner Corporation, Chicago, Ill., a corporation of Virginia

Application April 20, 1939, Serial No. 84,434

Term of patent 7 years

To all whom it may concern:

Be it known that I, Arthur Fuller Dean, a citizen of the United States, residing at Winnetka, in the county of Cook and State of Illinois, have invented a new, original, and ornamental Design for a Lubricant Dispensing Apparatus, of which the following is a specification, reference being had to the accompanying drawing, forming part thereof.

I claim:

The ornamental design for a lubricant dispensing apparatus, as shown.

ARTHUR FULLER DEAN.
